BY Charles Albert French
ATTORNEY

UNITED STATES PATENT OFFICE.

HARRIS MORGAN WHITCOMB, OF ALBANY, WISCONSIN.

SHOP-DOOR LATCH.

1,120,874.

Specification of Letters Patent. Patented Dec. 15, 1914.

Application filed April 1, 1914. Serial No. 828,938.

To all whom it may concern:

Be it known that I, HARRIS MORGAN WHITCOMB, a citizen of the United States, residing at Albany, in the county of Green 5 and State of Wisconsin, have invented certain new and useful Improvements in Shop-Door Latches, of which the following is a specification.

My invention relates to improvements in 10 door latches for shops and for which a patent was issued to me June 17, 1913, No. 1,064,800, but more particularly to the handles for the same, the construction and 15 method of attaching the said handles to the sliding plate of the latch and to the fulcrum plate attached to the opposite side of the door.

The objects of my invention are, to construct a simple and more convenient handle 20 which can be attached and held in position without the aid of the cotter pins employed in the previous and heretofore mentioned patent.

I attain these objects by the mechanism 25 illustrated in the accompanying drawings in which—

Figure 1, is a plan of my latch with the top of the bolt race removed and the handles 4 and 5, in section through the sliding plate, 30 Fig. 2, is a vertical section through a door and the latch on line R—S, Fig. 1. Fig. 3, is a longitudinal section on line T—U, Fig. 1. Fig. 4, is a plan of the fulcrum plate 6, Fig. 5, is a vertical section on line X—Y, 35 Fig. 4. Fig. 6, is a plan of the sliding plate 2, and Fig. 7, is a vertical section on line V—W, Fig. 6.

Similar numerals refer to similar parts throughout the several views.

40 The casing 1, is made from a plate of steel with a square bolt race raised and extending longitudinally through its middle line to the rear, which is closed and has a hole punched through it for the passage of the 45 tang 9 of bolt 3. Portions of the closure around the hole acting as the seat and rear stop for the actuating spring 7. On both sides of the bolt race just forward of the center are rectangular holes for the admission 50 and operation of the handles 4 and 5, and at the base of the bolt race above and joining the said rectangular holes are two narrow slots 8, to secure and guide the sliding plate 2. The four corners of the casing 55 are rounded and adjacent to the same are

holes for attaching screws. The sliding plate 2, is a rectangular plate of steel rounded at the corners and through which are punched two holes adapted to carry the four prongs of the two bifurcated handles 4, 60 and 5. The aforesaid holes are round on the left side and extending laterally to the right terminating in slots narrower than the diameter of the holes, adapted to lock the grooved portion or neck of the handle, 5, 65 against end play, when the free ends of the handle 4, are in the round portion of the holes.

From the rear side of said plate is removed a rectangular notch to adapt it to a 70 notch in the lower edges of the bolt 3, see Figs. 1 and 3, which it engages and to which it is operatively attached.

The bolt 3, is a steel channel angularly closed at the front end and terminating at 75 the rear in a round tang 9 adapted to carry the actuating spring 7, and having a portion removed from the lower edges to secure to and coöperate with the sliding plate 2.

The handles 4 and 5, are formed from a 80 bar of round steel straight on the front side, with semi-circular top and bottom sections terminating in two parallel prongs at right angles to the front. The said prongs are each adjacent the curved portions of the 85 handles, grooved on opposite sides forming necks, which secure the said handles in operative position in the slotted holes 10, one in the sliding plate 2, and one in the fulcrum plate 6, the free ends of both handles passing through the round holes in the opposite plates, thereto, thereby adjusting them to 90 various thicknesses of doors.

On the opposite side of the door from the casing 1, is a stationary member 6, which is 95 made from steel and contains two holes 10 round at one end and slotted laterally, corresponding to the holes in sliding plate 2, but are disposed with the slotted holes in one member opposite the round holes in the 100 other. The said member is secured to the door by four screws adjacent its corners being the fulcrum and in connection with plate 2, carries the two bifurcated handles 4 and 5, the grooved portion of the handles and the connection to the latch bolt being clearly shown in Fig. 3.

It is obvious that a force applied to the handles 5, in the direction of the arrow I, or applied to handle 4, in the direction of 110

the arrow J, would cause the bolt 3, to recede and disengage any suitable catch, thus allowing the door to be opened.

Having thus fully described my latch 5 what I claim as new and desire to protect by the issue of Letters Patent therefor is—

In a device of the kind described, in combination with a stationary member or casing having a bolt race, two apertures, two slots 10 and means for attaching to a door, a spring actuated bolt within the bolt race and engaging a sliding plate, a sliding plate having two round end slotted holes therein, adapted to hold one handle in locked position in the slotted portion by the round free end of a second handle, a fulcrum plate 15 rigidly attached to the opposite side of a door from the casing, the fulcrum plate having two round end slotted holes therein and

corresponding to the holes in the sliding plate, the round portion of the holes registering with the slotted portion in the sliding plate and the slotted portion registering with the round portion in the sliding plate, two handles with grooved portions adapted to fit within the slotted holes in the sliding plate and fulcrum plate and locked by the free round end of the opposite handle, the two handles extending through the door from opposite sides. 30

In testimony whereof I affix my signature in the presence of two subscribing witnesses.

HARRIS MORGAN WHITCOMB.
